COMBINATION LOCK

Willis D. George, Woodside, N. Y., assignor to The
Yale & Towne Manufacturing Company, Stamford,
Conn., a corporation of Connecticut

Application January 24, 1950, Serial No. 140,268

12 Claims. (Cl. 70—303)

1.

This invention relates to combination locks, and more particularly to means for preventing the detection of the combination of a lock of this class by experimental manipulation of the tumbler-setting mechanism.

It is the particular object of this invention to contribute a combination lock in which the known method of tapping the fence against the tumblers to determine their gating pattern cannot be successfully employed.

In locks of this class, even though the periphery of one or more tumblers prevents actual entry of the fence into any gating until all gatings are aligned, it has been found possible to detect the presence of a gating adjacent to the fence; that is, to detect when a tumbler is set, merely by tapping the fence against the tumbler assembly. This is accomplished by rapidly changing the direction of the tumbler-setting means, or dial, within a very small angle. The fence, being responsive to movement of the tumbler-setting means, it is possible to "feel" a reaction, different than normal, when the fence is rapidly tapped against the tumbler assembly in the presence of the gating of a set tumbler.

The ordinary sequence in which combination lock tumblers are set being known to those familiar with these locks, it is of course necessary only to detect, in proper order, the angular position of the gatings of the several tumblers, with reference to the dial reading, to elicit the combination of a particular lock.

Thus the present invention has as its primary object the provision of a combination lock in which this surreptitious method of deriving the gating pattern is unworkable.

The basic concept of my invention is the provision of means, within a combination lock, for preventing effective response of the fence to rapid oscillation of the dial.

Thus I provide a lost motion connection between the tumbler-setting means, or dial, and the fence itself, so that the fence is not responsive to a change of direction of such means until a movement thereof in a single direction through a very considerable angular distance has been accomplished before reversal.

So, by the introduction of means requiring relatively great alternate rotations of the dial to effect oscillation of the fence, I may render it impossible for the hand of a manipulator to accomplish with sufficient speed and accuracy a response in the fence useful in this common method of ascertaining the tumbler pattern of the lock.

The gist of my invention resides in the intro-

2.

duction of a lost motion connection between the dial and the fence, but it will be understood from the following description that this may be accomplished in several ways within the scope of the invention.

In a preferred embodiment of the invention I utilize a couple between the dial and the driver of the tumbler assembly to introduce a considerable lag in the response of said driver upon reversal of the dial, and provide means for frictionally urging the fence toward and away from the tumbler assembly, said means being actuated by the driver.

However, a modification herein described shows that equivalent results may be accomplished by rigidly coupling the dial to the driver in the usual manner, and by introducing a connection with considerable lost motion within frictional means actuated by the driver for urging the fence toward and away from the tumbler assembly.

In my lock I employ a usual gated tumbler assembly having a driver sequentially rotating the other tumblers, a dial for setting the tumblers, a fence adapted to enter the gatings of the tumblers when the same are aligned, and a bolt adapted to be retracted by the fence in the common manner. However, in my lock I provide means actuated by the driver for moving the fence toward and away from the tumbler assembly so as to avoid a positive connection between the driver and fence, and further provide, at any convenient stage in the train of cooperating parts from the dial through the fence, a suitable lost motion connection for preventing transmission of vibration from the dial to the fence.

I have thus outlined rather broadly the more important features of my invention in order that the detailed description hereof which follows may be better understood, and in order that my contribution to the art may be better appreciated.

There are, of course, additional features of my invention that will be described hereinafter and which will form the subject of the claims appended hereto. Those skilled in the art will appreciate that the conception on which my disclosure is based may readily be utilized as a basis for the designing of other structures for carrying out the several purposes of my invention. It is important, therefore, that the claims be regarded as including such equivalent constructions as do not depart from the spirit and scope of my invention, in order to prevent the appropriation of my invention by those skilled in the art.

Referring now to the drawing, Figs. 1, 2, 3, and 4 illustrate a preferred embodiment of my invention. Fig. 1 is a section through a door showing this embodiment of my combination lock applied thereto, the lock itself being shown in section taken on the lines 1—1 of Fig. 2. Fig. 2 is the section taken on the lines 2—2 of Fig. 1. Fig. 3 is the section taken on line 3—3 of Fig. 2. Fig. 4 is a perspective view of the driver tumbler structure.

Figs. 5 and 6 illustrate a modification of the invention. Fig. 5 corresponds generally to Fig. 2. Fig. 6 is the section taken on the lines 6—6 of Fig. 5.

The preferred embodiment of the invention shown in Figs. 1 through 4 will be described first.

In the drawing, the reference numeral 10 indicates the usual type of combination setting dial used in combination locks of the present class, the dial being positioned on one side of a door 11. The combination lock itself is enclosed within a suitable casing 12 from which extends a tube 13. The dial 10 is fixed to a usual spindle 14, the spindle extending through the tube 13 and a driver 15 and a concentric boss 16 mounted on the rear face of said driver. See Fig. 1. The structure of the driver is best seen in the perspective view of Fig. 4, wherein the boss 16 is shown to be of stepped heights, the lower surface thereof being designated 17 and the higher surface 18, and the steps being indexed 19 and 20. The inner end of the spindle 14, on which the driver 15 is normally free, is provided with a key 21. In Fig. 4, to clarify the structure, the spindle 14 is shown thrust abnormally rearwardly with respect to the driver 15 so that the configuration of the boss 16 is not obscured. However, it will be understood that in assembly the key 21 abuts the lower surface 17 of the boss, as shown in Fig. 2, and that the driver 15 and the spindle 14 are consequently free to rotate relatively to each other through the angular distance of surface 17 between steps 19 and 20.

The driver 15 is adapted, through the usual means well known in the art, to rotate a tumbler 22, that in turn rotates a tumbler 23, that in turn sets a tumbler 24. In other words, the rotation of the dial 10 will, through the spindle 14, set the several tumblers 15, 22, 23, and 24 so as to align their respective gatings relatively to the bolt-retracting fence of the lock. The assembled tumblers are best shown in Fig. 1.

In the usual manner each tumbler is provided with a gating. The gating of the driver is designated 25. Those of tumblers 22, 23, and 24 are respectively designated 26, 27, and 28.

Insofar as I have described my invention it is of the usual and standard construction well known in the art, but with the important exception that spindle 14 and the driver tumbler 15 are capable of relative rotary movement within a limiting angle determined by the steps 19 and 20 at either end of the surface 17 of boss 16 on which key 21 may ride. When the key 21 strikes either step 19 or step 20, continued rotation of the dial 10 positively rotates the driver 15.

Mounted for sliding movement within the casing 12 is a bolt 29 having a locking nose 30 and two tail pieces 31 and 32. The tail pieces 31 and 32 are adapted to slide in contact with guide surfaces provided at 33 and 34 within the casing 12. The locking nose 30 is adapted to be thrown and retracted through an aperture 35 in one wall of casing 12, shoulders 36 limiting the throw of

said locking nose. Tail piece 31 of the bolt is provided with a rabbeted slot at 37 within which an arm of the fence is loosely received. See below; compare Figs. 2 and 3.

For retracting the bolt 29, I utilize a fence 38 having the form of a bellerank pivotally mounted on a post 39 driven into the casing 12 at 40. An arm 41 of the fence is received slidably and with considerable tolerance within the slot 37 of tail piece 31 of the bolt. It will be obvious from Fig. 2 particularly that counterclockwise movement of the fence operates to retract the locking nose 30. Another arm 42 of the fence is provided at its outer end with a gating-entering portion in the form of a fence bar 43. The bar 43 is of such length that it extends from the front to the rear of the pile of tumblers. See Fig. 3, particularly, which shows the edges of the tumblers with the fence bar extending across all of them. Thus, the bar 43 necessarily must enter all gatings simultaneously. In other words, the bar cannot enter any gating until all gatings are aligned, for the periphery of any unregistered tumbler will prevent entry of the bar and consequent operation of the fence. The peripheries of the several tumblers are of common radius (Figs. 1 and 3).

Secured to the front face of the driver tumbler 15 is a spur gear 44 which meshes with another spur gear 45 pivotally mounted on post 39 in front of the fence 38. The only restraint against relative rotary movement of the gear 45 with respect to the fence 38 is friction.

As the dial 10 is rotated with the key 21 in driving contact with step 19 or step 20 of the boss 16, the driver 15 is, of course, positively driven by the dial, and gear 45 is driven by gear 44. Thus, according to the direction of effective driving rotary movement of the dial 10, the fence 38, in frictional contact with gear 45, is subjected to a drag tending to swing it toward or away from the tumblers. This drag, however, is positively restricted in one direction by the slot 37 of the bolt, and in the opposite direction by the periphery of one or more tumblers unless, of course, all tumbler gatings are in alignment and registered with the fence bar 43. Under this last condition the fence bar enters the aligned gatings and further rotation of the tumblers effects retraction of the bolt by positive counterclockwise drive of the arm 42 of the fence.

It is, of course, possible to cause the fence bar to strike the tumblers repeatedly by a series of relatively violent reversals of the dial, but it will be noticed in Figs. 2 and 4 that the lag represented by the angular spacing of steps 19 and 20 of the boss 16 is very considerable and may even be greater than shown, and must be overcome before the fence is responsive to the dial. A rapid series of reversals of the dial through an arc sufficiently great to rotate positively the driver 15 each time is not only extremely difficult for the hand of a manipulator, but is practically impossible to do without overthrowing and thereby causing the fence bar to strike the tumblers at a different radial position every other reversal. Therefore, in the present structure, any effective vibration of the fence bar against the tumblers at a given setting is out of the question.

A modification of my invention is illustrated in Figs. 5 and 6. Fig. 5 corresponds to Fig. 2 of the embodiment described above. Fig. 6 is a sectional plan view of the modification.

Herein the driver 15 is keyed at 46 to the spin-

dial 44 so that the connection between the dial 10 and the driver is rigid. In this structure the boss 16 and the key 21 are omitted. Mounted on post 39 for rotary movement in frictional engagement with the fence 38 is a disk 41. The disk 41 is positioned between fence 38 and gear 45, but the disk is mounted on post 39 so that it may rotate freely with respect to gear 45.

The disk 41 is provided with a tooth 48 occupying but a few degrees of the periphery of the disk. Mounted on gear 45 is a pin 49 adapted to strike the tooth 48 in one of two relative positions of the disk and gear, such positions being, in one direction, nearly a full turn of the gear (see Fig. 5). Thus, on contact of the pin and tooth, if rotation of the dial, driver and the two gears is continued, the disk is positively driven in step with gear 45.

Here, as distinguished from the first embodiment, the dial, spindle, driver, and the two gears rotate invariably together. However, it is clearly seen in Fig. 5 that the introduction of the disk 41 with its tooth 48 between the fence 38 and gear 45 with its pin 49, that a lost motion connection is provided between the tumbler-setting means and the fence, whereby rapid oscillation of the said means within a small angle cannot accomplish a responsive oscillation of the fence for the purpose of tapping the tumbler assembly.

I now claim:

1. A lock of the class described comprising a series of tumblers having gatings, a fence adapted to enter said gatings when the same are aligned, actuating means whereby said fence is moved toward and away from said gatings, a dial for setting said tumblers, and further means whereby said dial actuates said actuating means for moving said fence toward and away from said gatings, said further means comprising a lost motion connection whereby said dial moves freely of said actuating means during part of its rotation.

2. A lock of the class described comprising a series of tumblers having gatings, a fence adapted to enter said gatings when the same are aligned, actuating means whereby said fence is moved toward and away from said gatings, a dial for setting said tumblers, and further means whereby said dial actuates said actuating means for moving said fence toward said gatings, said further means comprising a lost motion connection whereby said dial moves freely of said actuating means during part of its rotation.

3. A lock of the class described comprising a series of tumblers having gatings, a fence adapted to enter said gatings when the same are aligned, a bolt retracted by said fence when the same enters said gatings, actuating means whereby said fence is moved toward and away from said gatings, a dial for setting said tumblers, and further means whereby said dial actuates said actuating means for moving said fence toward and away from said gatings, said further means comprising a lost motion connection whereby said dial moves freely of said actuating means during part of its rotation.

4. A lock of the class described comprising a series of tumblers having gatings, a fence adapted to enter said gatings when the same are aligned, a bolt retracted by said fence when the same enters said gatings, actuating means whereby said fence is moved toward and away from said gatings, a dial for setting said tumblers, and further means whereby said dial actuates said ac-

tuating means for moving said fence toward said gatings, said further means comprising a lost motion connection whereby said dial moves freely of said actuating means during part of its rotation.

5. A lock of the class described comprising a driver and tumblers mounted for rotation, said driver and said tumblers having gatings, a fence adapted to enter said gatings when the same are aligned, means actuated by said driver urging said fence toward said tumblers during rotation thereof in one direction and away from said tumblers during rotation thereof in the reverse direction, a rotating dial, and a lost motion connection between said dial and said driver constructed for introducing a lag between reversal of said dial and reversal of said driver.

6. A lock of the class described comprising a driver and tumblers mounted for rotation, said driver and said tumblers having gatings, a fence adapted to enter said gatings when the same are aligned, a bolt retracted by said fence, means actuated by said driver urging said fence toward said tumblers during rotation thereof in one direction and away from said tumblers during rotation thereof in the reverse direction, a rotating dial, and a lost motion connection between said dial and said driver constructed for introducing a lag between reversal of said dial and reversal of said driver.

7. A lock of the class described comprising a series of tumblers mounted for rotation on a common axis, said tumblers having gatings, and one of said tumblers being a driver rotating the other tumblers sequentially, a pivotally mounted fence adapted to enter said gatings when the same are aligned and to be rotated thereby, a gear mounted on said driver, a further gear in frictional engagement with said fence whereby rotation of said further gear produces a drag on said fence, said further gear being in mesh with said first-named gear, a dial for setting said tumblers, and a lost motion connection between said dial and said driver.

8. A lock of the class described comprising a series of tumblers mounted for rotation on a common axis, said tumblers having gatings, and one of said tumblers being a driver rotating the other tumblers sequentially, a pivotally mounted fence adapted to enter said gatings when the same are aligned and to be rotated thereby, a bolt adapted to be retracted by said fence when the same enters said gatings and is rotated thereby, a gear mounted on said driver, a further gear in frictional engagement with said fence whereby rotation of said further gear produces a drag on said fence, said further gear being in mesh with said first-named gear, a dial for setting said tumblers, and a lost motion connection between said dial and said driver.

9. A lock of the class described comprising a series of tumblers mounted for rotation on a common axis, said tumblers having gatings, and one of said tumblers being a driver rotating the other tumblers sequentially, a pivotally mounted fence adapted to enter said gatings when the same are aligned and to be rotated thereby, a gear mounted on said driver, a disk in frictional engagement with said fence whereby rotation of said disk produces a drag on said fence, a further gear coaxially mounted with said disk but free for rotary motion relative thereto, a post on said further gear and a peripheral tooth on said disk adapted to be engaged by said post, said further

gear being enmeshed with said first named gear, and a dial for setting said tumblers.

10. A lock of the class described comprising a series of tumblers mounted for rotation on a common axis, said tumblers having gatings, and one of said tumblers being a driver rotating the other tumblers sequentially, a pivotally mounted fence adapted to enter said gatings when the same are aligned and to be rotated thereby, a bolt adapted to be retracted by said fence when the same enters said gatings and is rotated thereby, a gear mounted on said driver, a disk in frictional engagement with said fence whereby rotation of said disk produces a drag on said fence, a further gear coaxially mounted with said disk but free for rotary motion relative thereto, a post on said further gear and a peripheral tooth on said disk adapted to be engaged by said post, said further gear being in mesh with said first-named gear, and a dial for setting said tumblers.

11. In a lock of the class described having gated tumblers and a fence adapted to enter the gatings of said tumblers when said gatings are aligned, a friction drive, means whereby one of said tumblers acts through said friction drive to urge said fence toward said tumblers during rotation of said one tumbler in one direction and away from said tumblers during rotation of said

10

15

20

25

one tumbler in the opposed direction, and said means including between said one tumbler and said fence a loose connection allowing free movement of said one tumbler relatively to said fence in at least one direction.

12. In a lock of the class described having a dial, gating tumblers rotated by said dial, and a fence adapted to enter the gatings of said tumblers when said gatings are aligned, a friction drive, means whereby said dial acts through said friction drive to urge said fence toward said tumblers during rotation of said dial in one direction and away from said tumblers during rotation of said dial in the opposed direction, and said means including between said dial and said friction drive a loose connection allowing substantial free movement of said dial relatively to said fence in at least one direction.
